The ornamental design for a wearable device with graphical
user interface, as shown and described.

DESCRIPTION

See application file for complete search history.

The file of this patent contains at least one drawing/photograph
executed in color. Copies of this patent with color
drawing(s)/photograph(s) will be provided by the Office
upon request and payment of the necessary fee.

FIG. 1 is a front view of a wearable device with graphical
user interface showing the claimed design;

FIG. 2 is another embodiment thereof; and,

FIG. 3 shows an environmental wearable device to which
the designs of FIGS. 1-2 may be applied.

The outermost broken lines in FIGS. 1-2 show a wearable
device having a display screen, and form no part of the
claimed design. The other broken lines in FIGS. 1-2 show
portions of the graphical user interface that form no part of
the claimed design.
